UNITED STATES PATENT OFFICE.

IVALOU B. SAMIS, OF LOS ANGELES, CALIFORNIA.

EDUCATIONAL GAME.

Application filed October 20, 1926. Serial No. 142,861.

This invention relates to safety games and is particularly adapted for use among children. This game is played on a suitable board which may or may not be foldable, 5 and the players may employ the use of dice or a specially constructed suitable roulette adapted to comply with the terms of the game board in forming additive score.

This game is an educational game. It 10 has as an object the instilling of safety habits, both personal and public in the minds of young children. A habit becomes fixed and is best acquired by repetition and drill on the receptive minds of young children. Through the medium of this safety 15 game which is called "Go-Stop", thoughts leading to the practice of safety rules and public hygiene are impressed upon the child's mind in an easy and pleasant manner. Through play and the spirit of competition an otherwise difficult and sometimes unpleasant idea is readily fixed in the child's mind permanently.

Another object of this invention, beyond 20 the thought of acquiring safety habits, is to provide a game through the playing of which one is taught to become alert. Good judgment is acquired by playing the right piece in the right manner. Most games 25 which employ the use of dice or the roulette are considered entirely games of chance. This game, although it does employ the use of dice or roulette, offers benefits that are seldom offered by other games of chance.

30 With the foregoing and other objects in view which will be made manifest in the following detailed description and specifically pointed out in the appended claims, reference is had to the accompanying drawings for an illustrative embodiment of the 35 invention, wherein:

Figure 1 is a plan view of the foldable board, upon which this game is played. This board being shown in extended position.

40 Fig. 2 is a plan view of the roulette device which is used in connection with the foldable board shown in assembled relation.

Fig. 3 is a perspective view of the specially constructed dice which may be used in playing this game.

45 Fig. 4 is similarly a perspective view showing a number of rectangular, oblong pieces which in this game represent the school children.

Referring to the accompanying drawings

wherein similar reference characters designate similar parts throughout, the board upon which this game is played is designated at 1. This board may be constructed 60 of any suitable material such as card-board or the like, and may be formed in two or more sections as at 2, 3 and 4. Printed, or otherwise indicated, on the inner face of this foldable board is a route shown by 65 numerals 5, 6 and 7. This route, which represents the path a child would take in proceeding from his home to his school, may be traced from the point marked "Go" indicated at 8, through a series of turns representing the various streets and corners to the point marked "Stop" shown at 9. These two points "Go" and "Stop" are the respective starting and finishing points of the game and are preferably located at points 70 75 on the board which are diametrically opposed. This route 5, 6, 7 is divided into spaces 10, each of which, when taken in an additive manner, represents the corresponding advance made by the "child" in his 80 hazardous path to school. Certain of these sections 10 are colored as in 11, 12, 13 and 14 and have upon them printed directions all of which relate to instructions ordinarily given at home to children just before they 85 leave for school.

Indicated at 21 is a specially constructed roulette particularly adapted to fit the terms of this game. This roulette comprises a circular base 22, having a pin 23 centrally 90 mounted upon the same. Revolvably associated with this pin is an arrow 24 which is adapted to be spun by the players. The base 22 is divided into sectors 25, 25, and upon each sector is printed a number (as 95 shown) which represents a move to be taken by the "child" on the board 1. Two of these sectors 26 and 27 are devoid of a number and in lieu thereof are printed the words "Stop" and "Go" respectively which will be 100 referred to hereinafter.

30 and 31 are cubical dice similar to those used in playing backgammon or in playing the ordinary game of dice. One of these dice 30 has a green surface on which the usual number has been omitted and the word "Go" inserted, and also a red surface on which another number has been omitted and the word "Stop" inserted. The other dice 31 is of the usual type and is preferably 105 arranged so that the opposite surfaces have numbers thereon, the sum of which equals 7. 110

Shown at 41 are a series of colored rectangular oblong blocks, which may be constructed of wood or any suitable material, representing the "children" of pieces employed in this game.

The method of playing above described game is as follows:

There may be four or less players. Each player has a certain number of "school children," and it is necessary the number of "children" each player has be the same. When four people are playing it is well to have two "children" for each player. With less than four players each player may have three or four of these rectangular, oblong blocks, or "children," who are supposed to be learning to observe the rules of personal and public safety.

The players may, at their own option, either spin the arrow on the roulette wheel or shake the dice in an effort to decide which player opens the game, or this choice may be determined in any suitable manner by mutual agreement. Other players take their turn in the game in the order of their seats at the table. As in similar games, or in cards, the players may take their turns passing to the right in a clock-wise manner. However, the players may prefer by mutual agreement to take their turns passing to the left in counter clock-wise manner. This, however, is immaterial but the various preliminary methods of opening the game should be determined among the players by mutual agreement and each man should conform to the rules thus adopted.

The game is opened by the player who has precedence over the others spinning the dial of the roulette wheel or shaking the dice. Since a more varied combination of numbers and consequently a more interesting result may be obtained by shaking the dice instead of spinning the dial, for purpose of illustration it will be assumed that the players have agreed to use the dice. The game can not actually be commenced on the board until one player has shaken a "Go." This permits him to enter a "child" in the race. When the player has thus shaken a "Go" he must enter a "child" on the board and proceed with this "child" from the "Go" sign as many spaces as the count on the other dice. He must, however, always use the entire count. If one die comes to rest on the word "Stop" that player loses his turn and count and the next player takes his turn. When all of one player's "children" are entered on the board and the dice come to rest on a "Go" he must use the count which appeared on the other die and shake again. The spaces on the route have printed instructions thereon. Certain of the spaces are designated as school crossings and these crossings represent places of safety where the "children" are not to be harmed. If a

"school child" happens to be on one of these school crossings he cannot be knocked off or sent back to start over his route in the manner hereinafter described. At any other place the "school child" may be sent back to start over. If another player's "school child" comes to rest upon the same space which that "child" is occupying or if this "child" comes to rest upon a space which indicates that he has committed some infringement of personal or public safety and is to be penalized, he may be sent back to start over, or penalized a certain number of points, this number of points being predetermined by printed rules accompanying the game.

Certain of the spaces are colored red and on them are printed minor or graver infractions of the rule of public health or safety, while certain other of the spaces are printed green and on them are written certain compliances with these rules of public health and safety, or certain good deeds that the child may perform. When a "child" comes to rest upon one of these red spaces he is sent back or penalized a corresponding distance set forth on the printed instructions and determined by the seriousness of his misdemeanor. If, however, he comes to rest on the green space he is correspondingly rewarded and is advanced a certain number of spaces similarly depending upon the virtue of his good deed.

The "children" of opposed players cannot occupy the same space at the same time except at school crossings where all children are supposed to be safe. A "child" who already occupies a space must return "home" and wait to be entered on the "Go" sign and started over when another player's "child" comes to rest alongside of him on this space. Two "children" of the same player may occupy the same space and, when this occurs, what is known as a blockade is formed. Two "children" of opposed players occupying the same school crossing also form a blockade. A player may pass another at any place except at a blockade. The player who succeeds in entering all of his "children" in the goal, which is indicated by a red circle marked "Stop," wins the game and if there are more than two players, the remaining players may continue the game to contend for second and third honors.

The above description clearly outlines the manner in which this game is played. However, certain important rules of this game have been set aside and will be outlined below. The players must accept their turn when it falls due and cannot refuse to play in turn. When dice are used the combined addition of points shaken may be used entirely in advancing any one "child" on its course, or this addition may be broken as determined by the dice. A player may not

break up the point shaken on a single die. In games of this nature it is customary that the player must determine his move before he touches any piece on the board and once 5 he has done so he is compelled to play this piece its entire count. This serves to teach the child the principle of caution.

I have chosen to color the space upon which a "child" is to be penalized red as 10 this is the color usually given stop signs and danger signals throughout the various traffic codes in different cities. Similarly, I have chosen to color other spaces green as this is the color usually given to "Go" signals and 15 to safety lights and it is believed that this coloring will have an important effect on the child's mind and will also serve to give the child the proper association of these colors with danger and safety.

20 It is obvious that I have provided a game which holds interest and enthusiasm for the younger children and which guides them in the way of safety and which, by means of penalizing them when they commit a 25 misdemeanor, firmly impresses upon their mind certain unhygienic or unsafe practices which are detrimental to their health or safety. For example, it is dangerous for a young child to put pins in his mouth and 30 in order to impress this upon the child I have provided a red space on the route. When one of the player's "children" lands 35 on this space he is penalized and is made to return back ten spaces. It is in this manner that the game works the desired effect upon the minds of young children.

It will be understood that various changes may be made in the details of the construction without departing from the spirit and 40 scope of the invention as defined by the appended claims.

I claim:

1. The combination with an educational game of the character described, a pair of dice, one of said dice having on its opposed surfaces numbers, the sum of which equals 7, the other of said dice having two of its surfaces colored, one of these surfaces being colored green and the other of said surfaces 50 being colored red, said green surface having printed thereon in lieu of the number the word "Go," said red surface having printed thereon in lieu of the number the word "Stop," whereby a player may be instructed 55 in the way of safety.

2. The combination with an educational game of the character described, of a pair of dice, one of said dice having on its opposed surfaces numbers, the sum of which equals 60 7, the other of said dice having two of its surfaces colored, one of said surfaces representing red for danger, and the other of said surfaces representing green for safety.

3. In an educational game of the character described, a die, said die having numbers indicated on four of its surfaces, the remaining of said surfaces being marked with the terms "Go" and "Stop" respectively, the colors being green and red respectively. 65

4. An educational game comprising a game board having a single, predetermined, definite path for pieces movable by the respective players, leading from a starting point to a goal of ultimate high attainment, 75 said path representing the distance and directions travelled by a school child through the perils of city streets enroute to school, said path being divided into a plurality of spaces, each representing portions of said route, certain of said spaces being colored red and representing hazards of the infractions of the rules of personal health or public safety, to impress upon the undeveloped mind the associations between this color and 80 the sense of danger, other of said spaces being colored green, and representing simple acts in compliance with the rules of hygiene and public safety, to similarly impress upon the undeveloped mind the association between this color and safety, and a pair of dice associated with said board, said dice having certain of their surfaces colored red and green to also impress upon the mind the sense of danger and safety. 85

5. An educational game comprising a game board having a single, predetermined, definite path for pieces movable by the respective players, leading from a starting point to a goal of ultimate high attainment, 100 said path representing the distance and directions travelled by a school child through the perils of city streets enroute to school, said path being divided into a plurality of spaces, each representing portions of said route, certain of said spaces being colored red and representing hazards of the infractions of the rules of personal health or public safety, to impress upon the undeveloped mind the associations between this color and 105 the sense of danger, other of said spaces being colored green, and representing simple acts in compliance with the rules of hygiene and public safety, to similarly impress upon the undeveloped mind the association between this color and safety, still other of said spaces being colored and representing school crossings where absolute safety is insured, 110 and a pair of dice associated with said board, said dice having certain surfaces of the same 115 colored red and green, to impress upon the mind the same principles of safety and danger.

In testimony whereof I have signed my name to this specification.

IVALOU B. SAMIS.
